UNITED STATES PATENT OFFICE

CLARENCE D. HOTCHKISS, OF GEORGETOWN, CALIFORNIA

FIRE ALARM

Application filed June 27, 1928. Serial No. 288,696.

The present invention relates to improvements in signalling or indicating devices, and has reference more particularly to a fire alarm.

5 One of the important objects of the present invention is to provide a fire alarm that is particularly adapted to be placed near a stove or electric wires, so that when a fire occurs, the devices will explode and thus give 10 an audible signal warning of the imminent danger.

A further object is to provide a fire alarm which is simple in construction, inexpensive, strong and durable, and further well adapted 15 to the purpose for which it is designed.

Other objects of the invention will become apparent during the course of the following detailed description taken in connection with the accompanying drawing.

20 In the accompanying drawing, forming a part of this application and wherein like reference characters designate like parts throughout the several views:

Figure 1 is a front elevation of the fire 25 alarm embodying my invention, showing the same supported in an attaching bracket.

Figure 2 is a front elevation thereof, and

Figure 3 is a longitudinal sectional view 30 through the device per se.

35 In the drawings, wherein for the purpose of illustration is shown the preferred embodiment of my invention, the numeral 1 designates a cylindrical shell that is preferably constructed of brass, the same being closed

35 at its inner end, while the open outer end of the shell is cut to provide the bendable strip 2 as clearly illustrated in Figures 2 and 3. The inner closed end of the shell is slightly enlarged to provide a rim portion 3 and 40 arranged within this rim portion is the percussion element 4.

The shell is partially filled with an explosive powder 5. The wad of any suitable material and denoted by the reference character 45 6 is arranged within the shell to maintain the explosive powder in a packed manner in the inner end portion of the shell, and a wooden block 7 is placed in the forward or outer end of the shell against the wad 6, 50 after which the bendable arms or strips 2

are directed inwardly against the front face of the block 7 as indicated in Figure 3. The adjacent strips are then soldered together, as at 8, thus providing a closure for the forward end of the shell and furthermore causing the 55 cartridge to explode from the side rather than from the forward end when the explosive powder is ignited.

The fire alarm cartridge is adapted to be supported in close proximity to the stove or 60 electric wires, by means of a suitable bracket 9 that is formed with an opening to accommodate the shell 1, and the rim portion 3 of the shell will be disposed against the rear face of the bracket and this bracket is adapted 65 to be secured to the stove pipe or any other support by any appropriate fastening means shown at 10.

The use of an alarm of the above mentioned character is thought to be readily obvious to those skilled in the art to which the present invention relates and when a fire breaks out, the cartridge will be exploded, thus giving an audible signal and warning 70 the occupants of the house of their imminent 75 danger.

While I have shown the preferred embodiment of my invention, it is to be understood that various changes in the size, shape and arrangement of parts may be resorted to, 80 without departing from the spirit of the invention and the scope of the appended claims.

I claim:

1. In a fire alarm signal, a cartridge comprising a shell open at its outer end and adapted to contain an explosive mixture, a packing in the outer end of the shell for the explosive mixture, the outer end of the shell being sealed to effect the side explosion of 85 the cartridge.

2. In a fire alarm signal, a cartridge comprising a shell open at its outer end and adapted to contain an explosive mixture, a packing in the outer end of the shell for the explosive mixture, the outer end of the shell being sealed to effect the side explosion of 95 the cartridge, and attaching bracket for the cartridge.

3. In a fire alarm signal, a cartridge com- 100

- prising a shell open at its outer end and adapted to contain an explosive mixture, a packing in the outer end of the shell for the explosive mixture, bendable strips at the open outer end of the shell adapted to be disposed inwardly across the packing, said strips being soldered together to seal the outer end of the shell and cause side firing of the cartridge.
4. In a fire alarm signal, a cartridge comprising a shell open at its outer end and adapted to contain an explosive mixture, a packing in the outer end of the shell for the explosive mixture, bendable strips at the open outer end of the shell adapted to be disposed inwardly across the packing, said strips being soldered together to seal the outer end of the shell and cause side firing of the cartridge, the closed inner end of the shell being formed with a rim portion, and an attaching bracket disposed over said shell and engaging with said rim portion.

In testimony whereof I affix my signature.
CLARENCE D. HOTCHKISS.
